UNITED STATES PATENT OFFICE.

ELMER L. SOHN, OF EL PASO, TEXAS.

CIGARETTE PACKAGE.

Application filed August 23, 1920. Serial No. 405,244.

To all whom it may concern:

Be it known that I, ELMER L. SOHN, a citizen of the United States, residing at El Paso, in the county of El Paso and State of Texas, have invented certain new and useful Improvements in Cigarette Packages, of which the following is a specification.

This invention relates to a novel cigarette package as well as to the method of dispensing or extracting cigarettes from the package and as well to the method of making a cigarette package.

An object of this invention is to provide a cigarette package which may be opened as it is usually opened by the user of the cigarettes without leaving a ragged edge and without the destruction of the cigarettes.

A further object of this invention is to provide a cigarette package having a weakened part at the top end whereby the corner may be torn from the package and cigarettes removed therefrom without destroying the cigarette or disfiguring the package.

A further object of this invention is to provide a cigarette package which will keep the cigarettes sealed and at the same time will provide a means whereby the corner may be removed from the package and cigarettes removed from the corner without opening the entire top of the package.

A further object of this invention is to provide an easily opened edge of a cigarette package which will not open the package to the middle thereof and yet which will at the same time render easy removal of the cigarettes therefrom without admitting of the cigarettes working out of the package.

A further object of this invention is to provide an improved method of manufacture of a cigarette package cover and to provide a method of weakening a certain portion of the wrapper which is of simple and inexpensive manufacture and in which a perforating rule is quickly adapted to accomplish the weakening at the desired position.

With these and other objects in view, the invention consists in the construction, the detail, and the arrangement of parts, and the methods hereinafter more fully described and claimed.

In the drawings:

Figure 1 is a perspective of my improved package intact.

Figure 2 is a perspective the same as Figure 1, except that one of the members 3 has been removed.

Figure 3 is a plan view of the innermost wrapper spread out.

In the embodiment of my invention there is provided an innermost wrapper for a cigarette package 1 of the conventional form which is weakened at 2, preferably by ruled perforations which, as shown in Figure 3, are semicircular in form at the bottom and extend vertically from the ends of the semicircle in parallel lines. The center from which the semicircle is struck is the crease line of the first fold for the package at a point midway between the folds for the narrow sides of the package, and the semicircle is of such radius as to extend beyond the said side to an extent approximating the difference between the radius of said semicircle and half the width of the said side. As shown in Figures 1 and 2, when this weakened part is folded over it provides a cap for the corner, which cap extends downwardly upon the package to approximately one-fifth of the length of the package and extends around the side of the package in the form of a quadrant, and extends over the top of the package about two-thirds of the distance from the edge of the package to the revenue stamp 4 conventionally sealing the top of the package and provides a straight line across the top of the package by the parallel lines 2^a which, when the package is folded at the V-form indicated by the numeral 5, causes the ends of the lines 2^a to meet at 6 and when folded the tearing line 80

clears sufficiently the underlapping portions of the V 5 as to produce a complete and even tear across the top of the package. When this part 3 is removed from the corner, the cigarettes are exposed with two rows having the tops exposed and having the sides exposed sufficiently downward so that they may be readily grasped by the finger without digging down from the top into the package, which is often encountered in packages in which only a portion of the top is removed. Frequently, users of cigarettes will tear the corner of the package with a view of getting at the cigarettes in the package 100

without tearing the revenue stamp, or without tearing sufficient of the package to cause the cigarettes to automatically escape there-

from on being carried, and in so tearing the package, in the present method, frequently tear the package too far, and also leave it with ragged and unsightly edges, and also 5 frequently injuring the cigarettes in so doing. In the present package, however, the corner will naturally follow the weakened line, and when once started, is easily torn into a perfect and true configuration of a 10 hole and without injury to any of the cigarettes, and leaves just sufficient space to enable the removal of the cigarettes without admitting of the cigarettes working from the package.

15 In the manufacture of this cover, all that is necessary is to bend a pair of printer's rules in an arcuate form at the bottom, as shown in Figure 3, and insert them into a form and the whole improvement is accomplished.

20 Around the aforesaid wrapper 1. is the usual foil wrapper which is imperforate. Around the foil wrapper is the usual cup shaped wrapper, which is open at the top, 25 but perforated along the lines of the perforations of the innermost wrapper. The foil wrapper being imperforate preserves

the quality of the cigarettes and tears with the perforations in the paper.

What is claimed is:

1. In a cigarette package a cover member provided with a pair of parallel weakened lines terminating in a semicircle adjacent each end of said member and arranged so as to extend around an upper corner of 30 the package and include within the weakened lines overlapped end portions of the closure members of the package.

2. In a cigarette package, a package forming blank including side and end portions with closure members extending along opposite edges thereof, said blank having substantially semicircular weakened lines at one side of the blank and extended over a part of each side and end portion and parts 40 of one of the closure sections of the blank so that when the blank is assembled the ends of each substantially semicircular weakened line will be brought together and the line will extend over and around one corner of 45 50 the package including the folded over closure member.

In testimony whereof I affix my signature.
ELMER L. SOHN.
